METAL CABINET DOOR

Albert Golden, Chicago, Ill., assignor to Interstate Metal Products Company, Chicago, Ill., a corporation of Illinois

Application February 2, 1938, Serial No. 188,264

5 Claims. (Cl. 189—46)

This invention relates to improvements in door construction, and more particularly to insulated and reinforced sheet metal doors suitable for sheet metal or steel cabinets.

5 Doors for cabinets of the class of structure herein contemplated are necessarily of compact construction, light in weight and formed of the same sheet metal of steel as the cabinet body proper, and are usually as light in weight as possible in order that the cabinets can be moved about or placed where necessary. These doors for reasons of economy and expediency in structure are formed of as small a number of parts as possible, and the entire outer face of the door 10 is generally stamped out of a single sheet.

Since these cabinets are primarily adapted for use in offices and homes it is highly important that they are made as neat or decorative as possible, that the exterior surfaces are smooth and 15 unmarred, and that they can be painted or enameled without any surface irregularities, marks, lines or indentations appearing on the exposed faces of the finished cabinet.

Since the cabinets and doors are made of single 20 thicknesses of sheet metal of generally 24 or 26 gauge, it is necessary to reinforce the door to prevent it from becoming deformed and to give it body especially in cabinets of large size, and it is also necessary or at least highly desirable to 25 sound insulate the doors to reduce the metallic sounds when the door is closed.

Heretofore doors in cabinets of this kind have been reinforced and sound insulated by welding or otherwise securing to the inner side of the 30 door a strip of metal running lengthwise thereof. Welding this strip to the door by any method caused indentations or weld markings on the outer surface of the door which could not be entirely covered by paints or enamels, and the 35 resulting product had an irregular dented or marred appearance which detracts from the beauty of cabinet and its salability. Other methods have been adopted such as nesting a liner within the side flanges of the door and welding it to the side flanges. However, such latter methods have been slower and more costly and necessitated brazing or torch welding without satisfactory results.

It is therefore the object of this invention to 40 provide a sheet metal cabinet door having an improved sound insulating and reinforcing structure.

Another object is to provide an improved door structure of the class described wherein all structural parts are spot welded to each other.

Another object is to provide a sheet metal door having a sound insulating and reinforcing lining secured to it so that the surface of the door is free from markings, burns, or indentations, and which can be painted or enameled to yield a 5 smooth, glossy, unmarred and uniform surface.

Other objects relate to details and economy of structure which will be apparent from a consideration of the following specification and drawing, wherein:

Fig. 1 is a perspective view of a sheet metal or steel cabinet provided with a door embodying my improved construction.

Fig. 2 is a broken transverse section through the door on the line 2—2 of Fig. 1.

Fig. 3 is a partial vertical section of the door on the line 3—3 of Fig. 1.

Fig. 4 is a partial transverse section of the door on the line 4—4 of Fig. 1.

Referring to the drawing, 10 indicates a sheet 20 metal or steel cabinet suitable for storage, shop, office or household use, and is formed of stampings of 24 or 26 gauge sheets. One or more doors 11 may be suitably hinged thereto and provided with closure means.

The door comprises an outer or face portion 12 stamped out of a single sheet of metal and is formed integrally with inwardly extending flanges 13 at the top and bottom edges which may be finished off with the in-turned seams 14. The 30 sides of the door are likewise provided with the flanges 15, one or both of which may be finished off with the in-turned seams 16.

In order to give strength and rigidity to the door and prevent its deformation, and also to 35 provide a pocket to receive insulating material, the filler 17 is provided. The vertical edges of this filler are stamped to provide channels 18 which comprise the webs 19, inner flanges 20 and outer flanges 21. The filler is adapted to nest 40 within the flange 13 and 15 of the door, so that the flanges 21 of the filler lie inside of, and against the flanges 15 of the door, while the webs 19 of the filler lie against the inner surface of the door facing 12. In practice the flanges 15 of the door 45 may be bent slightly inwardly so as to make an angle of less than 90° with the inner surface. This permits the filler to be snapped inwardly and be held in place during the welding operations, and also forms a secure fit of the two parts.

The flanges 20 of the channel are of a depth sufficient to space the liner 17 from the door 12 to provide a pocket wherein insulating material such as, for example, the corrugated paper boards 22 may be placed. It is of course under- 55

stood that various kinds of insulating material known to the art may be employed instead, and they may be adhered to the liner or carried in the pocket formed by it and the door facing. The outer flanges 21 of the channels are preferably of a depth slightly less than that of the door flanges 15, and may, or may not partly overlie the seams 16.

The channels 18 are as narrow as they can be expediently made so as to provide a maximum expanse of the liner surface between them, and also sufficiently wide only to the extent of enabling one spot welding electrode to be temporarily received. The formation of the channels at the vertical edges of the filler 17 also serves to strengthen it and the webs 19 which lie against the inner surface of the door facing 12 also act as reinforcing ribs. The liner is joined to the door facing by spot welding the outer channel flanges 21 to the door flanges 15 by clamping the parts between the electrodes of a spot welding device, and causing spot welds 29 to be made at several vertically spaced apart points, the number being dependent upon the length of the door. Thus the only points of jointure are along the door flanges, and no weld marks are caused on the face of the door. Also by means of providing a channel, which may be very narrow, a rapid and efficient spot weld may be made.

If desired, in order to prevent undue bending or displacement from its relative parallel position, the liner may be aided in being uniformly spaced from the door panel by providing it at its remaining opposed edges, in this case the top and bottom, with angle irons 23, which may be spot welded to the liner as at 24, by means of one leg, the other leg freely abutting against the door panel. Other angle iron pieces of varying lengths such as 25 may be used to provide reinforcement at necessary points, and welded inside the liner as at 26, adjacent the portions of the structure which carry the lock 27 and door handle 28.

Although I have shown and described certain features of my improvement for the purpose of illustration, it will be apparent to one skilled in the art that various changes may be made in the details and form of construction without departing from the spirit of my invention, and therefore I do not wish to be specifically restricted thereto except as so limited by the appended claims.

I claim as my invention:

1. A sheet metal door structure comprising a facing panel having flanges formed at its edges and extending inwardly substantially perpendicular thereto the edges of said flanges terminating in overlapped seams, a liner for said panel formed with channels on opposed edges thereof, the said liner being positioned within the flanges of said panel so that the outer flanges of the channels lie against the flanges of the panel and the seamed edges thereof with the webs of the channels lying against the inner surface of the panel, the major body portion of the liner being held in spaced relation to the panel, the said outer flanges of the liner lying against the panel flanges and overlapping their seams and being united by means of spot welds.

70 2. A sheet metal door structure comprising a

facing panel formed with integral inwardly extending flanges and an insulating reinforcing liner nested therein having channel portions stamped integrally therewith on two opposed edges and angle bars secured to said liner adjacent its other two opposed edges, the webs of said channels and the perpendicularly extending legs of said bars lying against said panel to form stiffening ribs therefor and to hold said liner in parallel spaced relation thereto and forming a pocket therewith adapted to contain sound insulating material, the outer flanges of said channels being spot welded to complementary panel flanges.

3. A sheet metal door structure comprising a facing panel formed with integral inwardly extending marginal flanges, an insulating and reinforcing liner nested within the flanges of said panel, the said liner being formed with integral relatively narrow channel portions on at least two opposed longitudinal edges and bars provided with perpendicularly extending legs secured to said liner adjacent the top and bottom and intermediate thereof, the webs of said channels and the legs of said bars lying against said panel and holding the body of said liner in spaced parallel relation to said panel forming a pocket therewith, and insulating material contained in said pocket, the said liner being secured to said panel by spot welds formed between the outer flanges of said channels and the flanges of said panel against which they lie.

4. A sheet metal door structure comprising a facing panel formed with integral flanges extending therefrom at substantially a right angle, a liner for said panel adapted to reinforce it and support insulating material for said door, the said liner being formed with integral channel portions on at least two opposed edges, the webs thereof lying against said panel and the outer flanges thereof lying against the flanges of the panel and being spot welded thereto whereby the body of said liner is held in spaced parallel relation to said panel to form a pocket therewith, insulating material contained in said pocket, and spacing and reinforcing members secured to the inner side of said liner and abutting against the inner side of said panel.

5. The method of making a reinforced and insulated sheet metal door structure which comprises forming a flanged door panel from a single sheet with the flanges on the vertical edges thereof extending at an angle of slightly less than 90° to the inner panel face, forming a reinforcing and insulating liner thereof having channels stamped integrally therewith on the vertical edges thereof, the said channels being relatively narrow and having their flanges extending at substantially right angles to said liner, the width of said liner overall being substantially the width of said panel between the base of its vertical flanges, forcing the said liner in between the opposed panel flanges to cause the outer flanges of said channel to lie snugly against the said flanges of the panel, and spot welding the said flanges together by clamping them between opposed electrodes of a spot welding device.

ALBERT GOLDEN.
